(57) **CLAIM**

The ornamental design for a news box, as shown and described.

DESCRIPTION

FIG. 1 is a front and left side perspective view of a news box showing my new design;

FIG. 2 is a top plan view thereof;

FIG. 3 is a front elevation view thereof;

FIG. 4 is a rear elevation view thereof; and,

FIG. 5 is a right side view, the left side being a mirror image thereof.

The broken line showing of the roof, base, legs, and panel details is included for the purpose of illustrating portions of environment of the news box and forms no part of the claimed design.
